UNITED STATES PATENT OFFICE.

BARTLETT R. WILLIAMSON, OF SAN FRANCISCO, CALIFORNIA.

KNOCKDOWN BASKET.

Application filed February 9, 1922. Serial No. 535,156.

To all whom it may concern:

Be it known that I, BARTLETT R. WILLIAMSON, a citizen of the United States of America, and a resident of the city and county of San Francisco, State of California, have invented a new and useful Knockdown Basket, of which the following is a specification.

My invention relates to knock-down baskets for fruits, berries and other uses.

10 One of the objects of the invention is to provide a basket which may be packed and shipped flat and assembled into basket form by the hands of the user at the time when the basket is to be filled.

15 My invention possesses other objects and features of advantage, some of which, with the foregoing, will be set forth in the following description of the invention. It is to be understood that I do not limit myself to 20 the showing made by the said description, as I may adopt variant forms of my invention within the scope of the claims.

25 Referring to the drawings, Fig. 1 is a perspective view of the assembled basket. Figs. 2 and 3 are end elevations of the basket. Fig. 4 is a plan view of the basket members in flat assembly.

In general terms, the basket of my invention comprises shaped and scored members 30 cut from any suitable sheet material. The flat pieces are partially assembled together in the relation required, but without folding, and then permanently fastened. The pieces in flat assembly are then bundled and shipped. The unsecured ends of the basket members are provided with any suitable 35 snaps or fasteners readily applied or manipulated by the fingers, so that at the time of use the flatly assembled sheets may be 40 quickly folded into basket form and held by the snaps. In flat assembly much larger numbers of baskets may be handled conveniently at one time and a very material saving in shipping space is effected. Storage space is 45 also saved and because the basket form may be attained without tools they may be folded up at the moment of use, thus avoiding the inconvenience and waste characterizing the conveyance and handling of stacks of baskets in the usual form.

More particularly, my device comprises three members, two of which are duplicates. The bottom panel 2 is formed with end panels or flaps 3. In addition to the bottom 55 panels, there are two side panels 4, each of which is provided with end panels or flaps

6. In each piece the panels are separated by suitable score lines 7 to facilitate folding. The panels are conveniently shaped, substantially as shown in Fig. 4, the bottom panel forming the bottom of the box, the two side panels forming the side of the box and the end panels superposing one upon the other to form the end of the box. The various members are arranged in flat assembly, 60 as indicated in Fig. 4, the end panels 6 at one end of the two side panels being laid upon one of the end panels 3 and secured in place by wire stitches 8 or similar suitable fastening means.

65 Arranged in the free end panel 3 and one of the end panels 6 are snaps 9 or other similar readily engageable or interlockable fastening means, so positioned as to be in alinement when the members are folded 70 into the basket form, as shown in Fig. 1. The other end panel is provided with holes 11. This panel is inserted between the other two and the snaps engaged thru the holes, so that all three are secured.

75 While in the flat assembly, as shown in Fig. 4, the knock-down basket is bundled for shipment and is handled and stored in this condition until it is desired to use the basket, when the panels are brought into basket assembly and the snaps engaged.

80 While, ordinarily, fruit and berry baskets are used but once, there are some uses in which it may be desirable to disengage the snapped portions for storage between 85 seasons, and this may readily be done with my basket.

I claim:

1. An article of manufacture from which a basket may be folded, comprising a bottom forming member, a pair of side forming members, all of said members being scored to divide the end portions thereof into sections foldable relative to the remainder of the member to provide end forming sections, and means permanently securing the end forming sections at one end of each of said side members and bottom member together in superimposed end forming relation, the free ends of the side members extending diagonally from 95 each side of the bottom forming member.

100 2. An article of manufacture from which a basket may be folded, comprising a bottom forming member, a pair of side forming members, all of said members being scored to divide the end portions thereof into sections foldable relative to the remainder of 105

the member to provide end forming sections, means permanently securing the end forming sections at one end of each of said side members and bottom member together in superimposed end forming relation, and means for temporarily fastening the other end of each of the members in end forming relation when folded to form a basket.

3. A flat pattern adapted to be arranged in superimposed relation for shipping from which a basket may be formed, comprising a bottom forming member and a pair of duplicate side forming members, all of said members being separate from each other and

shaped and transversely scored to provide 15 fold lines, means for permanently securing one end of said side members and bottom member in superimposed relation with the side forming members, one extending diagonally from each side of the bottom forming member, and the free ends of said member being provided with readily engageable hand operated means which come into alignment when the members are folded into basket form. 20

25 In testimony whereof, I have hereunto set my hand.

BARTLETT R. WILLIAMSON.
